(57) **CLAIM**

The ornamental design for a household washer, as shown and described.

DESCRIPTION

FIG. 1 is a top plan view of a first embodiment of the household washer showing my new design;

FIG. 2 is a bottom plan view thereof;

FIG. 3 is a front elevational view thereof;

FIG. 4 is a 45° rotated side elevational view thereof;

FIG. 5 is a top plan view of a second embodiment of the household washer showing my new design;

FIG. 6 is a top front perspective view thereof;

FIG. 7 is a 45° rotated side perspective view thereof;

FIG. 8 is a bottom plan view thereof;

FIG. 9 is a top plan view of a third embodiment of the household washer showing my new design;

FIG. 10 is a top front perspective view thereof;

FIG. 11 is a 45° rotated side perspective view thereof;

FIG. 12 is a bottom plan view thereof;

FIG. 13 is a top plan view of a fourth embodiment of the household washer showing my new design;

FIG. 14 is a top front perspective view thereof;

FIG. 15 is a 45° rotated side perspective view thereof;

FIG. 16 is a bottom plan view thereof;

FIG. 17 is a top plan view of a fifth embodiment of the household washer showing my new design;

FIG. 18 is a top front perspective view thereof;

FIG. 19 is a 45° rotated side perspective view thereof; and,

FIG. 20 is a bottom plan view thereof.
